EYEGLASS CONSTRUCTION

George E. Nerney, Attleboro, Mass., assignor to
 Bay State Optical Company, Attleboro, Mass., a
 corporation of Maine

Application February 29, 1940, Serial No. 321,373

7 Claims. (Cl. 88—47)

This invention relates to eyeglass construction and more in particular to a rimless mounting for supporting lenses.

One of the objects of this invention is to provide an eyeglass construction which will be simple, practical, and thoroughly durable. Another object is to provide a construction of the above character having a minimum of parts and capable of easy assembly. Another object is to provide a construction of the above character which is neat and attractive in appearance. A further object is to provide a construction of the above character wherein the size of the non-transparent parts are reduced to a minimum to give a pleasing effect. Another object is to provide a construction of the above character which may be readily and inexpensively manufactured in large quantities. Another object is to provide a construction of the above character which will be sturdy and durable under the strain of extended use. A still further object is to provide a construction of the above character wherein the parts are reliably secured to the lens and to each other. Another object of this invention is to provide a construction of the above character having a minimum of angles and crevices in which foreign material may collect. Other objects will be in part obvious and in part pointed out hereinafter.

This invention accordingly consists in the features of construction, combinations of elements, and arrangements of parts as will be exemplified in the structure to be hereinafter described, and the scope of the application of which will be indicated in the following claims.

In the accompanying drawing, in which is shown one of the various possible embodiments of my invention,

Figure 1 is a front elevation of an eyeglass frame having my construction mounted thereon;

Figure 2 is a horizontal section taken along the line 2—2 of Figure 1;

Figure 3 is an exploded perspective view on an enlarged scale of a portion of the construction shown in Figure 1; and

Figure 4 is a perspective view on an enlarged scale of a portion of the construction shown in Figure 1.

Similar reference characters refer to similar parts throughout the several views of the drawing.

This invention relates to that disclosed in my copending application Serial No. 322,278, filed March 5, 1940, entitled "Eyeglass construction,"

and for certain details of construction and operation reference may be had to that application.

In order to set forth a more comprehensive understanding of certain features of this invention, it might be here pointed out that considerable difficulty has been experienced in rimless eyeglass construction in attempting to achieve a reliable and durable connection between a fitting and the lens. A large part of this difficulty results from improper fitting of the lens by the retailer at the time of sale, from loosening of the screw when the eyeglasses are in use, and from strains caused by twisting of the temples. These factors often result in lens fracture, necessitating replacement of the lens with the resultant expense.

As is well known, appearance is one of the paramount factors in eyeglass construction, and, accordingly, in rimless eyeglass construction, it is desirable to make the nontransparent parts as small and inconspicuous as possible. Difficulty is experienced, however, in constructing a small and thus inconspicuous fitting, and, at the same time, achieving a strong and durable connection between the lens and the fitting. Another object of this invention is to provide a construction of the above character in which the above-mentioned difficulties, in addition to many others, are successfully and efficiently overcome.

It might here be noted that any reference hereinafter to a "rearward" direction refers to a direction toward the face of the wearer, and a "forward" direction refers to a direction away from the face of the wearer. Also, a "downward" direction indicates a direction downwardly toward the foot of the drawing, while an "upward" direction is the opposite thereof. The "rear" surface of the lens denotes that surface nearest the face of the wearer, and the "front" surface of the lens denotes the opposite surface.

Referring now to the drawing in detail, there is shown in Figure 1 a pair of lenses 10 and 70 supported by a lens mounting. This mounting comprises a pair of temple-supporting arms 11 and 41 connected to lenses 10 and 70 by a pair of endpieces 14 and 43 and joined together by a bridge 12. Nose pads 13 and 42 are mounted on nose pad arms, which serve the additional purpose of forming a part of endpieces 14 and 43, all as will be more fully described hereinafter.

In the description below, particular reference will be made to the construction shown at the right of Figure 1; the construction at the left of the figure is the same, though, of course, reversed in assembly.

Endpiece fitting 14 (Figures 2 and 3) is formed by a portion of nose pad arm 15 having an end portion 22 and a pair of saddle fittings, generally indicated at 16 and 17. Saddle fittings 16 and 17 are preferably made from resilient sheet metal, illustratively, spring steel; saddle fitting 16 is formed with a leaf spring section 18 and an integral ear 19. Saddle fitting 17 is substantially similar to saddle fitting 16, having a leaf spring section 20 and an integral ear 21. However, leaf spring section 18 is longer than leaf spring section 20, and ears 19 and 21 extend outwardly from opposite sides of their respective spring sections. When the endpiece fitting is assembled (see Figures 2 and 4), leaf spring section 18 lies along the edge of the lens with ear 19 extending along the rear side of the lens. Leaf spring section 20 lies along the longer leaf spring section 18, and ear 21 extends along the front surface of the lens substantially in alignment with ear 19. The end 22 of nose pad arm 15 extends along ear 21 to the edge of the lens and thence rearwardly across the edge of the lens at the centers of spring portions 18 and 20. Saddle fittings 16 and 17 are rigidly clamped to nose pad arm 15 at the centers of their respective leaf spring portions 18 and 20 by means of a rivet 36. Rivet 36 (see Figure 3) is soldered to leaf spring portion 18 and extends through a hole 25 in leaf spring portion 20 and a hole 24 in nose pad arm 15, where it is headed over.

As best seen in Figures 2 and 3, ears 19 and 21 are provided with enlarged outer ends 26 and 27, which outer ends are cup-shaped with the periphery of the cups contacting the lens surfaces. These enlarged ends, lens 10, and the enlarged end of the end portion 22 of nose pad arm 15 have holes formed therein which holes, when the mounting is in place on the lens, are in alignment and receive a screw 28 which threads into the hole formed in end portion 22. When screw 28 is tightened, the peripheries of the cup-shaped ends 26 and 27 of ears 19 and 21 are forced tightly against the surfaces of the lens to thereby clamp the lens, and, at the same time, the main portions of the resilient ears follow the curvature of the lens. When the screw is set, the center portions of cup-shaped ends 26 and 27 resiliently press away from the lens, preventing the rotation of screw 28. Thus the present construction prevents loosening of the screw, which very often results in lens breakage. Furthermore, the lens is clamped and supported in a manner to prevent uneven tensioning by the ears on the lens; in the past, uneven tensioning has also resulted in lens breakage.

Referring now to Figure 2, the tightening of screw 28 also serves to draw the leaf springs into closer contact with their respective lens edges. To accomplish this, hole 50 in the enlarged end of ear 19 is preferably made of substantially the same diameter as screw 28. As screw 28 is tightened, hole 50 normally would tend to pass through an arc having the juncture point 60 between the lens edge and the rear surface of the lens as its center. However, as the sides of hole 50 abut against screw 28, it is prevented from moving inwardly in the arc as it moves toward the concave surface of the lens. Thus, as screw 28 is tightened, an outward pull toward the lens hole is exerted on the fitting through ear 19, which pulls the leaf spring into close contact with the lens edge.

As best shown in Figure 4, nose pad arm 15

extends rearwardly from lens 10 and thence curves forwardly and downwardly where it supports nose pad 13. Temple-supporting arm 11 is soldered to the rearwardly extending portion of nose pad arm 15 rearwardly of endpiece fitting 14 so that the temple-supporting arm lies behind the edge of lens 10. Temple-supporting arm 11 extends upwardly from its point of connection to nose pad arm 15, and thence behind and along (see also Figure 1) the upper edge of lens 10 to connect with a temple (not shown). Bridge 12 is soldered to the upwardly extending portions of temple-supporting arms 11 and 41 and cooperates with the two temple-supporting arms in providing a reliable practical support for the two lenses.

It should be noted that screw 28 (see Figure 2) extends from the rear surface of lens 10 toward the front, so that the screw head 40, which is the part of the screw having the greatest diameter, is hidden from view when the eyeglasses are in use. Furthermore, the end of end portion 22, into which the end of screw 28 threads, is of a very small size. Thus, by extending the screw through the lens in this direction, the appearance of a rimless eyeglass construction is materially enhanced, as the size of the visible nontransparent parts are reduced. At the same time, such reduction in size does not deduct from the strength and security of the connection between the mounting and the lens.

Thus a strong and durable rimless mounting has been disclosed which fulfills the exacting requirements necessary when there is only one connection between the lens and the mounting. Furthermore, the resilient type of construction in the endpiece is particularly adapted to absorb the twisting strains transmitted to it through temple-supporting arm 11. Also it should be noted that the number of crevices and angles is at a minimum in the construction disclosed hereinabove with the result that this mounting will not collect a great amount of foreign material. Thus it will be seen that I have provided a thoroughly practical and efficient construction in which the several objects hereinabove referred to, as well as many others, are successfully accomplished.

As many possible embodiments may be made of the above invention, and as many changes might be made in the embodiment above set forth, it is to be understood that all of the material hereinabove set forth or shown in the accompanying drawing is to be interpreted as illustrative and not in a limiting sense.

I claim:

1. In eyeglass construction, in combination, a pair of lenses, a pair of temple-supporting members, a bridge connecting said temple-supporting members, a pair of arm members for connecting said temple-supporting members to said lenses, said arm members including portions extending over the front surfaces of said lenses, a pair of leaf spring members connected to each of said arm members, said leaf spring members extending along the edges of said lenses, an ear formed on each of said spring members, the ears of each pair of spring members extending over opposite surfaces of each of said lenses, and a pair of screws securing said ears and the portions of said arm members extending over the front surfaces to said lenses.
2. In eyeglass construction, in combination, a pair of lenses having a pair of lens holes formed therein, a pair of temple-supporting members,

5 10 15 20 25 30 35 40 45 50 55 60 65 70 75

bridge means connecting said temple-supporting members, a pair of nose guard arm members, a pair of nose guards mounted on said nose guard arm members, said nose guard arm members extending forwardly across the edges of said lenses and including portions extending over the front surfaces of said lenses, leaf spring members connected to each of said nose guard arm members and extending along the edges of said lenses, and an ear formed on each of said spring members, the ears of each pair of spring members extending over opposite surfaces of their respective lenses, and screws connecting each pair of ears and said arm members to their respective lenses, the heads of said screws contacting one of each pair of ears, whereby when said screws are tightened, said ears are drawn into adjusted relationship against said lenses.

3. In eyeglass construction, in combination, a lens having a lens hole formed therein, an arm member extending across the edge of said lens, a temple supporting member connected to said arm member, a portion of said arm member extending over the convex portion of said lens, a pair of leaf spring members secured to the portion of said arm member adjacent said lens edge, a resilient ear formed on each of said leaf spring members, said ears extending over opposite surfaces of said lens, one of said ears being positioned between the portion of said arm extending over the convex portion of said lens and said lens, and screw means extending through said ears and said hole and threading into said arm member, the head of said screw means contacting one of said ears, whereby said ears are drawn into adjusted relationship with said lens when said screw means is tightened.

4. In eyeglass construction, in combination, a lens, a temple supporting member, a pair of leaf spring members positioned in surmounted relationship on the inner edge of said lens, a single integral ear formed on each of said leaf spring members, said ears extending over opposite surfaces of said lens, means connecting said leaf spring members to said temple supporting member, and screw means connecting said ears to said lens.

5. In eyeglass construction, in combination, a

lens, a temple supporting member, a pair of leaf spring members positioned in surmounted relationship on the inner edge of said lens, a single integral ear formed on each of said leaf spring members, said ears extending over opposite surfaces of said lens, means connected to said temple supporting member including portions extending across the edge of and over one surface of said lens, a screw connecting said ears and said last-mentioned means to said lens, and means connecting said springs to the portion of said last-mentioned means extending across said lens edge.

6. In eyeglass construction, in combination, a pair of lenses, a pair of arm members, a bridge, means connecting said arm members to said bridge, said arm members each including portions extending across said lens edges and over a surface of each of said lenses, a pair of leaf spring members connected to each of said arm members, said leaf spring members extending along the edges of said lenses, a single integral ear formed on each of said spring members, the ears of each pair of spring members extending over opposite surfaces of each of said lenses, and screw means securing said ears and the portions of said arm members extending over the surfaces of said lenses to said lenses.

7. In eyeglass construction, in combination, a pair of lenses, a pair of arm members, a bridge, means connecting said bridge to said arm members, said arm members each including portions extending across the inner edges of each of said lenses and across portions of the front surfaces thereof, a pair of leaf spring members positioned on the inner edges of each of said lenses, means connecting each pair of leaf spring members to the portions of said arm members extending across said lens edges, a single integral resilient ear formed on each of said leaf spring members, the ears of each pair of spring members extending over opposite surfaces of each of said lenses, and a pair of screws extending through said ears and said lenses and threading into the portions of said arm members extending over the front surfaces of said lenses.

GEORGE E. NERNEY.
